UNITED STATES PATENT OFFICE.

HOWARD M. KILPATRICK, OF NEW YORK, N. Y.

COLLAR.

Application filed December 13, 1920, Serial No. 430,350. Renewed January 18, 1929.

My invention relates to soft collars and has for its object to provide a soft collar and means associated therewith whereby the front corners may be kept down and free of wrinkles.

To this end I provide a collar having a folded-over part having front corners, and comprising an outer fabric and a lining, the lining having slits in its upper part near the ends, and a flat weight to be slipped through said slits into said corners between the lining and said fabric, for holding said corners down and free of wrinkles. But it is understood that the invention, as claimed, is not limited to the details shown.

In the drawings, Fig. 1 is a perspective view of a collar having my invention embodied therein;

Fig. 2 is a face view of the collar flattened out;

Fig. 3 shows a section on the line 3—3 of Fig. 2;

Figs. 4, 5 and 6 are edge, face and end views of one form of weight;

Fig. 7 is a face view of another form of weight;

Fig. 8 is a fragmental inner face view of the corner of a collar, with another arrangement for attaching the weight; and

Fig. 9 is a perspective view of another form of weight and attaching means.

My invention is shown embodied in a soft fold-collar having a neck-band 10 and folded-over outer part 11 having front corners

12 and comprising an outer fabric 15 (Fig. 3) and an inner lining 16 stitched to said fabric at the edges to form a pocket space 17 in said corner. Said lining 16 is provided with a long button-hole-stitched slit 20

substantially parallel to and near the end of the seam 21 joining the neck-band 10 and said folded-over outer part 11, for giving access to said pocket space 17. Within each pocket space 17 in said corner 12 is disposed

a flat metallic weight 23 of lead or other suitable metal widely spaced from said seam 21 and having thick intra-marginal part 24 (Figs. 4 and 5) and thin edges 25, and a pointed lower end portion 26 fitting in said corner.

The weight, while heavy enough to hold the corners of the collar well down and free of wrinkles, is so small that it is not noticeable when the collar is worn. By having the weight widely spaced from the seam 21, free movement is permitted to the weight and

front of the collar as when the chin is thrown as far forward as possible on or toward the chest. The lead weight is, of course, flexible and an advantage of the flexibility of the weight is that the weight may be bent, after insertion, to give the corner of the collar a better set.

The slit 20 is placed near the seam 21 and edge 17 so these may assist in guiding the weights to the slit for removal of the weights before laundering. To remove the weights, it is merely necessary to hold the collar up by the corners 12, with one corner higher than the other, and both weights will pass out the same slit 20, being guided by the edge 17 and seam 21. After the collar has been laundered, the weights are slipped through the slits 20 and positioned in the corners 12 as in Figs. 1 and 2. Then the collar is worn in the ordinary way, the weights being not noticeable, either to the wearer or onlooker.

Instead of having the weights pointed, they may be round, as in the weight 27 of Fig. 7, which may appear an edge elevation as in Fig. 6.

Instead of having the pocket space 17 between the lining and outer fabric, a small triangular patch pocket 28 (Fig. 8) may be stitched to the inner face of the corner 12. Or, the weight 29 (Fig. 9) may be provided with a pin 30 and pin-receiving hook 31, whereby the weight may be secured to the inner face of the corner 12.

I claim as my invention:

1. In combination, a collar having lower end corners, and a weight carried by each of said corners and remotely spaced from the upper part of the collar.

2. In combination, a collar having a neck-band and a folded-over part having corners; and a weight removably carried by each corner remote from the upper edge of said folded-over part.

3. In combination, a collar having lower end corners, and a weight carried by each corner, and remotely spaced from the upper part of the collar and being sufficiently heavy to hold down the corner by the action of gravity.

4. In combination, a collar having lower end corners, and a flexible, inelastic metal weight carried by each of said corners.

5. In combination, a soft fold-collar having a neck-band and a folded-over part having front corners and comprising an outer

fabric and an inner lining stitched to said fabric at the edges to form pocket spaces in said corners, said lining being provided with a long button-hole-stitched slit parallel to 5 and near the part joining the neck-band and folded-over part; and a flat lead weight widely spaced from said seam and having thick intra-marginal part and thin edges, and a pointed lower end portion fitting in 10 said pocket space in each of said corners.

6. A soft collar having a neck-band, and a folded-over part having lower front cor-

ners and comprising a lining and a portion adjacent thereto, both of uniform thickness and stitched together at the side edges only 15 to form pocket spaces at said corners, said lining being provided near the end of the part joining the neck-band and the folded-over part with a horizontal slit, said folded-over parts being free of stitches connecting 20 the lining and adjacent portions at points between either slit and either lower front corner.

HOWARD M. KILPATRICK.
